REINFORCED LIGHTWEIGHT WRENCH
HANDLECarl H. Ingwer, Elyria, Ohio, assignor to The
Ridge Tool Company, Elyria, Ohio

Application December 10, 1949, Serial No. 132,362

7 Claims. (Cl. 81—101)

1

This invention relates to hand tools, and more particularly to a wrench having an adjustable jaw such as a monkey wrench or a pipe wrench.

In the past, wrenches including those having adjustable jaws have been made from a ferrous metal, either by a forging or casting process. Use of the heavy ferrous metal was necessary in order to obtain the required strength, since the light weight metal, such as aluminum or magnesium, did not have the requisite tensile strength. However, the handles of these wrenches and certain other parts were highly stressed for only a portion of their extent, with other parts being less highly stressed. For instance, the portion of the handle of a wrench actually grasped by the hand, and the part from the grip to the end of the handle, is subject to much less stress than is the part between the grip and the jaws of the wrench. Therefore, it is not necessary to use a high strength material there.

Some wrenches have taken advantage of this condition by using wooden blocks on either side of a flat extension of the handle. Others have used leather washers threaded over an extension and formed to the proper shape. Each of these devices pertained to the handle alone, however, and each was aimed primarily at the comfort of the user's hand while gripping the wrench, and only secondarily at lightening the weight of the wrench.

It is the purpose of my invention not only to ease the grip somewhat, but also to provide a light weight tool easy to carry and easy to handle. This is accomplished by providing reinforcement strips of a strong material about which the tool part may be cast from a light weight, non-ferrous material, to form the handle and/or other parts.

A more complete understanding of my invention will be gained from the following description and figures which form a part of this specification.

In the drawings:

Fig. 1 is a sectional view along line 1—1 of Fig. 2 and shows the core of a wrench built according to my invention;

Fig. 2 is a sectional view along line 2—2 of Fig. 1;

Fig. 3 is a view similar to Fig. 2 of an alternative cross section used by my invention;

Fig. 3a is a fragmentary elevation of the upper end of the insert shown in Fig. 3.

Fig. 3b is a section taken on the line 3b—3b of Fig. 3a;

Fig. 4 is a view similar to Fig. 2 showing a second alternative cross section;

2

Fig. 4a is a view similar to Fig. 3a of the insert Fig. 4.

Fig. 4b is a section taken on the line 4b—4b of Fig. 4;

Fig. 5 is a view similar to Fig. 2 showing still another alternative cross section;

Fig. 5a is a view similar to Fig. 3a of the modified insert shown in Fig. 5; and

Fig. 5b is a section taken on the line 5b—5b of Fig. 5.

Briefly, my invention comprises a wrench handle formed from a light weight metal or alloy preferably by casting. The required strength of the handle is provided by a steel core or backbone which reinforces the light metal, while at the same time the light metal supports the steel core to prevent buckling.

More specifically, and with reference to the figures, my invention comprises a wrench handle 11, shown in the figures as the handle of a pipe wrench but equally applicable to many other types of tool, such as monkey wrenches, adjustable end wrenches or the like.

A core 12 is firmly embedded in the case material of the handle 11. This core is preferably formed of steel and may be either a flat plate (Fig. 2), or it may take any of the shapes shown in Figs. 3—5, as a cross section. If, however, it is formed from a flat sheet, I prefer that a plurality of holes 13 be provided to hold the core or insert firmly in place. These holes should not be so numerous as seriously to weaken the core 12 and are preferably located near the ends where stresses are not too severe. When the metal is cast about the core, these holes are filled with that metal, and, therefore, it is impossible for the light metal to shift longitudinally of the core. Similar holes may be provided in the other embodiments, although they are less necessary be-

cause of the greater surface of steel exposed to the light metal, and therefore greater friction area and consequent decreased likelihood of slipping. In addition, small points, or pins, 15, may be provided in forming the core as in the case of the flat core, or by drilling through the web 16 or flanges 17 of the other sections and driving small pins therethrough. These pins serve to support the core in the mold, and after pouring, the ends are cut off and the surface is smoothed. The points 15, therefore, provide additional means for holding the core in place in the handle. An additional guard against slippage of the case metal on the core or insert 12 is provided by notches 18 formed in the core and which are filled with the case metal when the handle is cast.

A heel jaw 19 and a hook jaw 20 are provided

55

as is customary, although I have shown and prefer to use a heel jaw such as described in the copending application of Oscar E. Swanson, Ser. No. 97,980, filed June 9, 1949, now abandoned.

As is customary, the hook jaw extends through a boss 21 and is threadably engaged by an adjusting nut 22. The boss 21 is formed of the light metal, but provision is made to absorb a considerable part of the force on the hook jaw, in the core 12. This is accomplished by forming an extension 23 on the core which extends from the core to the under surface 24 of the boss 21. At this point, it is at the surface and is adapted to be engaged by the nut 22. The surface 24 is so formed in this region that the nut bears most heavily on the extension 23, and therefore a great deal of the force on the hook jaw 20 is absorbed in the core.

This extension 23 may be formed differently on the different cores dependent on the cross sectional shape. In the flat piece (Fig. 1) the extension is merely formed in the piece as it is cut. In the U-shaped core a tongue may be struck outwardly from the web 16 of the piece and be bent at right angles thereto to form the extension. Similarly, tongues could be struck from the flanges 30 of the T- and 31 of the I-shaped sections (Figs. 4 and 5) to form bifurcated extensions which would serve the same purpose.

Thus, it is apparent that I have provided a wrench sufficiently strong for most use while, at the same time, being considerably lighter and easier to handle. And this may be accomplished by any of several embodiments of my invention. Nor is my invention confined to pipe wrenches, but it may be used in many hand tools, although it is especially well suited to adjustable wrenches and the like.

Having thus described my invention, I am aware that numerous and extensive departures may be made therefor without departing from the spirit or scope of my invention.

I claim:

1. A wrench comprising a metal handle and having a boss extending laterally from the handle and formed with an aperture extending longitudinally therethrough, a hook jaw having a threaded shank extending through the aperture, an adjusting nut for said hook jaw disposed on said shank and having a pressure face confronting a fulcrum surface of the boss, metal reinforcing means for said handle composed of a material having greater strength than the other metal and disposed substantially throughout most of the length of the handle and adjacent said boss and being formed with a nut engaging projection, said

projection forming a portion of said fulcrum surface of the boss.

2. A wrench as claimed in claim 1 wherein the reinforcing means is T-shaped in cross section throughout most of its length.

3. A wrench as claimed in claim 1 wherein the reinforcing means is I-shaped in cross section throughout most of its length.

4. A wrench as claimed in claim 1 wherein the wrench is U-shaped in cross section.

5. A wrench as claimed in claim 1 wherein the reinforcing means is a flat metal strip substantially enclosed within the handle portion.

6. In a wrench having an adjustable jaw and nut means for adjusting said jaw, a handle for said wrench composed of a light weight material to shape said handle and a reinforcing core of strong material, said core extending interiorly of said handle throughout most of its length, but having a lateral extension passing through a portion of the handle and outwardly therefrom and constituting a high pressure bearing surface for said nut.

7. A handle for a wrench, said wrench having an adjustable jaw and an adjusting nut threadably disposed thereon for adjustment, said wrench also comprising a heel portion, a handle portion extending from said heel portion and terminating in a grip portion, a boss formed on said handle and extending laterally from said heel portion, said boss having a longitudinal opening therethrough to receive said adjustable jaw and having a fulcrum surface confronting a pressure face of said nut, said handle being formed of a light weight material having a core of high strength extending throughout most of its length, said core having a projection extending into said boss and the projection having a portion of its surface exposed for contact by the pressure face of said nut.
